DENTAL HAND PIECE

Floyd M. Hutchinson, Tiskilwa, Ill.

Application May 28, 1938, Serial No. 210,699

7 Claims. (Cl. 32—27)

This invention relates to the portion of a dental drilling machine known as an angle hand-piece, and particularly to the structure of the head by which the drill is removably carried. One object of the invention is to provide for the effective lubrication of the parts in a cleanly manner so that the internal mechanism can be practically sealed against leakage of lubricant when in use, but readily opened for the introduction of fresh lubricant when required. A further object of the invention is to arrange for the convenient manipulation of the chuck by which the drills are removably held so that they may be released or secured at will without opening the casing structure in which the moving parts are housed. Further objects will appear as the description proceeds. The invention consists in the several features and elements of construction in combination, as herein shown and described and as indicated by the claims.

In the drawings:

Figure 1 is an axial section showing the head and elbow portions of the hand-piece on a scale larger than the normal size of said parts, and illustrating the application of forced lubrication to the head for cleaning out the hand-piece.

Figure 2 is a section taken substantially at the common plane of the axes of the drill-holding chuck and the driving shaft which is geared thereto.

Figure 3 is an axial section taken through the head and chuck substantially at right angles to the plane of Figure 2.

Figure 4 is a transverse detail section taken at line 4—4 on Figure 2.

Figure 5 is a detail section taken at line 5—5 on Figure 2.

Figure 6 is a detail elevation showing a fragment of the top of the cap for the head.

Figure 7 is a sectional view similar to Figure 3, but showing a modified construction.

Figure 8 is a sectional view taken as indicated at line 8—8 on Figure 7.

Figure 9 is a transverse section taken at line 9—9 on Figure 8.

Figure 10 is a side elevation of the chuck and its driving sleeve, with its adjusting nut shown in section.

Figure 11 is a perspective view of the chuck as it appears when removed from the device.

The type of hand-piece shown in the drawings includes the usual body portion A, which is a sleeve containing suitable bearings for the section of drive shaft B, which it houses,—it being understood that this drive shaft is operated

through a flexible shaft connection, not shown. Adjoining the body A is the bent tubular housing or elbow C secured to the body A by a threaded connection at C¹, and enclosing a pair of crown gears D and D¹ through which the drive is transmitted from the shaft B. Rigidly associated with the elbow C is a neck portion E, which is made of reduced cross-section to afford a better view of the work. A section of drive shaft F is journaled in the neck portion E and connects the gear D¹ with a gear G at the opposite end of the shaft F. The gear G is disposed beyond the end of the neck E and within the housing which constitutes the head H of the hand-piece.

As seen in Figure 2, the head includes an approximately cylindrical portion 1 and a second cylindrical portion 2 joined to the first at right angles. The end of the shaft F carrying the gear G extends into the portion 2 being definitely located therein by the engagement of the threaded end 3 of the neck E with the internally threaded bore of the part 2. The end portion of the neck E is formed with a groove 4 into which the extreme end of the housing 2 telescopes; and to insure that when the parts are thus screwed tightly together, the bent elbow portion C shall lie in exactly the correct relation to the head H, a shim washer 5 of the proper thickness may be inserted in the groove 4. Within the head H, as may be best seen in Figure 2, the driving gear G meshes with the teeth of a gear 6 secured to the hollow spindle 7. The lower end of the housing 1 forms a journal bearing at 8 for the gear 6, and the opposite end of the spindle 7 is formed with an oppositely tapered portion 9 for which a correspondingly shaped bearing 10 is adjustably screwed into the upper end of the shell 1. Proper adjustment of the bearing 10 is maintained by a lock nut 11 screwed into the shell 1 just above the bearing 10.

The hollow spindle 7 carries a clutch sleeve 12 designed to removably hold the drills, such as that shown at J in Figure 1. The sleeve 12 is longitudinally slotted as seen at 13, either three or four slots being provided to render the sleeve compressible in the lower portion of its length, and at the extreme lower end said sleeve is formed with an outwardly flaring outer surface 14 of conical formation; the outer end of the hollow spindle 7 may be similarly flared at 15 with approximately the same taper, and this may be accomplished by swaging the end of the spindle outwardly to occupy a slight counterbore 55 in the end of the driven gear 6 for positioning

the gear on the spindle, as seen in Figures 2 and 3.

At its upper end the clutch sleeve 12 is fitted with a rigidly secured head 16 externally threaded to receive a nut 17 and the latter rides normally on the upper end of the tapered journal portion 9 of the hollow spindle 7. When the shank 20 of a drill J is inserted in the clutch sleeve 12, as shown in Figure 3, its upper end, if notched at 21, may interlock with the projection 22 provided on the specially formed closure 23 at the upper end of the sleeve 12; but the necessary frictional grip on the shank 20 for holding the drill firmly in place is supplied by contracting the clutch sleeve 12 about the shank. This is done by temporarily holding the nut 17 against rotation while allowing the spindle 7 to turn so that the threaded head 16 is forced upwardly toward the position shown in Figure 3, drawing with it the clutch sleeve 12 and forcing its flared end 14 into the hollow spindle 7 so that it may grip the shank 20.

As a convenient means for arresting the nut 17, or, at least, retarding its rotation in adjusting the clutch sleeve 12, I have shown a slide member 30 carried in the cap 25, which closes the upper end of the shell 1, and I have shown the nut 17 as of approximately square form (see Figure 4) but with its corners rounded as seen at 17^a, and with its upper edge beveled as at 17^b for engagement with the inclined stop surface 31 of the slide 30. The thumb-piece 32 of the slide 30 is accessible at the side of the cap toward the body A of the hand-piece so that the thumb of the hand which grasps the hand-piece may be readily caused to bear against the part 32, and shift the stop face 31 of the slide 30 into contact with the beveled surfaces 17^b of the nut 17, thus tending to arrest the nut if it be rotating, or to hold it still so that the rotation of the threaded head 16 in the nut 17 may shift the clutch sleeve 12 axially. It will be evident that if said rotation is in one direction, the clutch will be tightened upon the shank 20, but if the direction of rotation is reversed, the clutch will be released by movement of the threaded head 16 back to its original position shown in Figure 2. To insure positive rotation of the clutch sleeve 12 it is provided with a driving lug 26 projecting into a slot 27, which extends longitudinally through the tapered enlargement 9, which serves as a journal at the upper end of the spindle 7. If the nut 17 were threaded clear through, the rotation of the spindle in the direction for releasing the clutch sleeve 12 might tend to carry the threaded head 16 on the sleeve 12 beyond the lower face of the nut 17, causing the latter to travel upward toward the cap 25; however, as shown in Figure 2, this is prevented by providing the nut with an annular lip 17^c, extending inwardly at its lower end so as to limit the downward range of adjustment of the head 16 and prevent any tendency of the nut 17 to travel upwardly on the threads of the head 16.

By reason of its inclined formation, the stop portion 31 of the slide acts to limit the upward travel of the threaded head 16 of the clutch sleeve 12, preventing the head 16 from being shifted so far as to become wedged against the under side of the cap 25. This might otherwise occur if the parts were operated without a drill in the sleeve. It is also possible that during operation of the drill, the endwise pressure upon the latter may tend to shift the sleeve 12 axially in the spindle 7, wedging the flared end portions 14 a little 75

more tightly, and carrying the nut 17 out of contact with the journal portion 9 of the spindle; in this case the inclined relation of the shoulder 31 will cause it to exert an initial pressure axially of the sleeve 12 to effect an initial release of the tapered portions 14 from the end of the spindle at 15.

The slider 30 is formed with flaring edges 33 so that it fits an under-cut groove in the cap 25. 10 The thumb-piece 32 of the slider normally fits into a notch in the side wall of the cap 25 and the abutment or stop surface 31 is shown extending approximately at an angle of 45 degrees connecting the under face of the slider with the 15 thumb-piece portion. This requires the cap 25 to be slotted to accommodate the inclined stop portion 31, but the under-cut groove in the top of the cap is closely fitted to the slider, as is the notch in the side of the cap which the thumb-piece 32 occupies, so that the cap remains substantially oil-tight, notwithstanding the mounting of the movable slider in it. The movement of the slider is limited by a lug 34 on a terminal block 35 which is attached by a screw 36 to the 20 end of the slider after the latter has been inserted in the under-cut groove of the cap. The cap and its slider are thus retained in assembled relation.

The cap 25 being screwed onto the reduced upper end of the shell 1 is readily removed therefrom when desired, and may be thus removed for supplying the hollow head H with fresh lubricant when required. Preferably, a grease gun or similar device having a discharge tube or nozzle P with a threaded coupling Q as indicated in Fig. 1, will be screwed onto the reduced threaded portion 1^a of the shell 1 for thus supplying lubricant; and on such occasions the fresh lubricant will be forced throughout the cavity of the head H. The bearing for the shaft F in the end portion of the neck E may be formed with a longitudinal groove 40 which assists in conveying lubricant from the housing 1 through the neck E and into the elbow section C. The 35 threaded end of the elbow is also provided at 41 with a channel extending from the cavity of the elbow which houses the gears D and D¹ to the end of this part which abuts the end of the body A. When fresh lubricant is introduced into the casing 1 under pressure, as by means of a grease gun, it tends to force out the old grease by way of the passage 40, thence through the neck E and cavity of the elbow C through the channel 41. If desired, the elbow C may be provided with a 40 special vent normally closed by a screw plug, seen at 42, for releasing the old grease, but a simpler arrangement for this purpose is afforded by partially unscrewing the body A from the elbow C thus providing a temporary outlet at the end of the channel 41 through which the old grease may escape as it is forced along by the fresh grease; hence, when clean grease begins to emerge at this point it will be an indication that the old grease has been cleaned out, and that the tool is now ready for further use. Then, by again tightening the connection between the parts A and C, and replacing the cap 25, the hand-piece will be rendered leak-proof. At the same time, the internal adjustment of the chuck sleeve 12, by means of the nut 17 and slider 30, may be accomplished without any risk of releasing the lubricant to the external surface of the hand-piece.

Figures 7 to 11 illustrate a head construction for a hand-piece, in which certain of the details

are slightly modified as compared with those already described. In this form the head itself is not materially changed, and includes the cylindrical portions 1 and 2 arranged for connection to the neck section E. The spindle 50 carries a gear 51 which bears in the tapered lower end of the casing 1 at 52, and a second bearing for the spindle is shown at 53, screwed into the casing and engaging the tapered journal portion 54. The bearing 53 is held at adjusted position by a lock nut 55.

For removably holding the drills in the spindle 50, a clutch sleeve 56 is carried in the spindle and is provided with outwardly bent lugs 57 which engage longitudinal slots 58 and 59 in the upper end portion of the spindle above the journal portion 54. The lugs 57 project through the slots 58 and 59 into an annular groove 60^a, in an adjusting nut 60 which is screwed onto the threaded upper end 61 of the spindle 50. The bore of the spindle 50 which accommodates the clutch sleeve 56, includes a tapered shoulder 62, and the clutch sleeve 56 is formed with a corresponding tapered portion 63. The sleeve is formed with slots 64, opening through the lower end of the sleeve, and slots 64^a which extend to its upper end, so that when shifted axially in the spindle 50 the entire length of the sleeve 56 will expand and contract under control of the tapered surfaces 62 and 63 to release or grip the shank of a drill. Such shifting of the clutch sleeve 56 is accomplished by movement of the nut 60 up or down upon the threaded portion 61 of the spindle.

As shown in Figure 9, the nut 60 has flat side surfaces 65 which may be engaged by the flat face 67 of a slider 66. The slider 66 is set in the cap 68 of the cylinder 1 and is similar to the slider 30 already described, except that the face 67 which is engageable with the flat faces 65 of the nut 60 extends parallel to the axis of the spindle 50 instead of obliquely thereto. When the slider face 67 is pressed into contact with one of the flat faces 65 of the nut 60, while the spindle 50 is rotated, the clutch sleeve 56 will be shifted up or down, depending on the direction of rotation of the spindle. The slider is fitted into the cap in leak-proof fashion; and the cap 68 may be unscrewed from the cylindrical shell 1 for the introduction of lubricant when required.

It will be recognized that in either form of the device there is no necessity of a spring for returning the slider 30 or 66 to its normal position, out of contact with the flat-sided, clutch-adjusting nut, since the rotation of the nut itself will tend to shift the slider to a position tangent to its rounded corners, where it will not interfere with the normal operation of the drill. And a slight pressure on the thumb-piece 32 of the slider 30 or the corresponding part 69 of the slider 66 will retard or arrest the adjusting nut and operate the clutch when desired.

It will also be evident that a positive driving engagement between the spindle and the clutch sleeve is not essential. In the form of the device shown in Figures 2 to 5 the omission of the lug 26 would leave the clutch tube frictionally engaged with the hollow spindle, but adapted to slip in the event of excessive load on the drill, which would frequently be an advantage.

In most hand-pieces the head portion in which the spindle and its drill are carried is of such dimensions as to more or less obstruct the dentist's view of the point at which the drill is work-

ing. To minimize this difficulty the contour of the head 1 of the present design is tapered so that it narrows towards the point of the drill and permits of a reasonably good view of the work in progress.

While there is shown and described herein certain specific structure embodying the invention, it will be manifest to those skilled in the art that various modifications and rearrangements of the parts may be made without departing from the spirit and scope of the invention, and that the same is not limited to the particular form herein shown and described, except in so far as indicated in the appended claims.

I claim:

1. In a dental hand-piece which includes a hollow spindle, a head in which it is journaled and enclosed, a threaded cap for said head removable for the introduction of lubricant, a tubular clutch member in the spindle, said spindle and clutch tube having portions of their contacting surfaces inclined to their common axis, whereby longitudinal adjustment of the tube in the spindle tends to contract or expand the tube, a threaded part connected to the clutch tube for longitudinal movement therewith, a nut engaging said threaded part and a member slidably fitted in said cap having a portion engageable with said nut to resist rotation of the nut only and effect the longitudinal adjustment of the clutch tube while the spindle is rotating.

2. In a dental hand-piece which includes a hollow spindle, a head in which it is journaled and a split clutch tube in the spindle, said spindle and clutch tube having portions of their contacting surfaces inclined to their common axis, whereby longitudinal adjustment of the tube in the spindle tends to contract or expand the tube, a threaded part connected to the clutch tube for longitudinal movement therewith, a nut engaging said threaded part and formed with flat, laterally exposed faces, a member movably fitted in the head having a flat portion engageable with said lateral faces for arresting the nut alone while the spindle revolves, said member having an externally exposed portion positioned for operation by the thumb of the hand which holds the hand-piece.

3. In a dental hand-piece which includes a hollow spindle, a head in which it is journaled and a clutch member in the spindle arranged to be contracted or expanded by longitudinal adjustment therein, a threaded part connected to the clutch member for longitudinal movement therewith, a nut engaging said threaded part and means accessible outside the head and shiftable into arresting relation with the nut alone, said means including a portion for holding the nut against longitudinal movement to insure longitudinal adjustment of said threaded part and the connected clutch member while the spindle is rotating.

4. In a dental hand-piece, in combination, a hollow spindle, a clutch tube in the spindle and rotatable therewith, and a threaded nut, together with threaded means on one of the other two parts engaged with the threads of the nut, a head in which the nut is enclosed, and shiftable means guided in the head having an externally accessible portion and a portion inside the head engageable with the nut for holding only the nut against rotation while the spindle and clutch tube rotate, whereby the clutch tube is shifted longitudinally in the spindle.

5. In a dental hand-piece which includes a

hollow spindle, a head in which it is journaled and enclosed, a tubular clutch member in the spindle expandable or contractible by longitudinal adjustment therein, said spindle having a longitudinal slot and the clutch tube having a lug extending through said slot for positive driving engagement with the spindle, the slotted portion of the spindle being externally threaded, a traveler nut on said threaded portion having an inwardly open annular groove into which said lug projects, whereby adjustment of the nut on the spindle shifts the clutch therein, and means accessible outside the head and shiftable into arresting relation with the nut to effect adjustment of the clutch while the spindle is rotating.

6. In a dental hand-piece which includes a hollow spindle and a tubular clutch member in the spindle engaged for rotation therewith but longitudinally adjustable therein, a nut having threaded engagement with one of said members and having a transaxial shoulder engaged with the other member, a head in which one end of said spindle and one end of said clutch member, together with said nut, are enclosed, a cap for said head normally fixed thereon during opera-

tion of the hand-piece, the means for holding said nut against rotation comprising a member slidably fitted in said cap with a portion inside the cap engageable with said nut and having a portion externally accessible on the cap positioned for operation by the thumb of the hand which holds the hand-piece.

7. In a dental hand-piece which includes a hollow spindle member and a tubular clutch member in the spindle engaged for rotation therewith but longitudinally adjustable therein, a nut having threaded engagement with one of said members and having a transaxial shoulder engaged with the other member, a head in which one end of said spindle and one end of said clutch member, together with said nut, are enclosed, and shiftable means guided in the head having an externally accessible portion and a portion inside the head engageable with the nut for holding only the nut against rotation while the spindle and clutch member rotate, whereby the clutch may be adjusted longitudinally in the spindle.
